UNITED STATES PATENT OFFICE.

GEORGE JACOBS AND FREDERICK C. RUPPEL, OF DETROIT, MICHIGAN.

SIGNAL-LAMP.

1,337,230.

Specification of Letters Patent. Patented Apr. 20, 1920.

Application filed May 5, 1919. Serial No. 294,660.

To all whom it may concern:

Be it known that we, GEORGE JACOBS and FREDERICK C. RUPPEL, citizens of the United States, and residing at Detroit, in 5 the county of Wayne and State of Michigan, have invented a new and Improved Signal-Lamp, of which the following is a specification.

The present invention has reference to a 10 signal lamp for motor vehicles, its general object being to provide an inexpensive and satisfactory device whereby a signal is automatically given the driver of a following car as the speed of the leading vehicle 15 changes, particularly when it slows down. In the preferred embodiment of the invention, the operation of the device is dependent on the inertia or pendulum principle, but some of the features are useful in connection 20 with signals of a different nature, for example, wherein the signal circuit is completed on turning a steering wheel or upon actuating a separate switch.

One of the primary objects of the invention 25 is to provide a signal of the class set forth wherein the signal lamp is on the same general circuit as the tail lamp, thereby reducing the expense and simplifying the installation. Thus the signal lamp operates 30 without interfering with the tail light and only upon change in speed of the vehicle, under which condition it preferably gives a flickering light, one flash for each swing of the pendulum.

35 A further object is to provide a combined signal and tail lamp on the same general circuit, together with a switch on or associated with the lamp, for cutting out the tail light without cutting out the signal light.

40 Another object is to provide a highly desirable construction of the pendulum device whereby clearance is secured for the bulbs and bulb circuits, and whereby a broad rigid support for the moving parts is afforded.

45 Again, the invention provides a desirable disposal of the circuit wires so that they do not interfere with the movements of the pendulum.

Another primary object is to provide a 50 readily removable reflector and lamp construction whereby free access may be had to the lamp sockets and associated parts for inspection and adjustment purposes.

Another object is to provide a combined 55 tail and signal lamp wherein the tail light bulb is supported wholly from the signal

lamp reflector and between the arms of the pendulum, thereby rendering the device as a whole much more compact.

Another primary object is to dispense 60 with the use of a lens ring or the like in supporting the lens and the reflector.

Additional objects and advantages will appear from the following description of a preferred embodiment of the invention. 65

In the drawings, Figure 1 is a central longitudinal vertical section. Fig. 2 is a vertical section through the pendulum-supporting shaft. Fig. 3 is a plan view showing the device attached to its support. Fig. 4 is a rear elevation, the support being omitted. Fig. 5 is an enlarged fragmentary section corresponding to Fig. 1. Fig. 6 is an elevation of the switch which appears in Fig. 1. 75

In the construction shown, the sheet metal lamp body, in order to permit the metal being readily drawn in the dies, is formed in halves 1 and 2 that may be welded together along the line 3, Fig. 2. The forward portion of the body forms a chamber for the bulb devices, said chamber, in this instance, being substantially the shape of two overlapping superposed cylinders or ovals 4-5, or somewhat resembling the figure 8; and 80 the rear or pendulum receiving portion 6 corresponds approximately to a sector of a cylinder whose axis is at right angles to those of the cylinders previously referred to. It will be observed, Fig. 3, that the 85 elements 4-5 and 6 merge along shoulders 7, through which the lamp as a whole may be supported, as by means of the screws 8 and a suitable bracket construction 9. 90

The cylindrical portions 4-5 are preferably provided with an out-turned flange or seat 12 from which the metal is extended forwardly in the shape of a centering and supporting ring or margin 13, which throughout a considerable angle along the 95 lower side of the portion 5 is curved upwardly and inwardly as indicated at 14, Figs. 1 and 4, whereby the lens 15 is properly supported when the resilient retaining latch device 16 (riveted or welded to the body at 17) is snapped down over its upper edge. In assembling the lens, it is only necessary to engage its lower edge in the support 14 and thereafter swing it bodily inwardly until it passes the hook of the latch; 100 likewise it is readily removable when the latch is elevated, as will be obvious. That 105

part of the flange 12-13 which corresponds to the cylinder 4 receives the out-turned flange 18 of a reflector (preferably parabolic) 19 to properly support the latter and exclude dust.

Mounted to swing about a horizontal axis approximately the center of curvature of the cylindrical sector 6 is a pendulum which in the preferred construction comprises a pair 10 of spaced arms 20, the bob 21 and the hollow combined spacer and pivot 22 on the reduced end portions of which the arms 20 swing. The element 22 is itself carried on the cross-bolt 24, and is spaced from the sides of the 15 body by the washers 26 that may be spot welded to the inner face of the corresponding side of the body. When the nut 27 is loosened and the bolt withdrawn, the pendulum may be lifted out through the lens opening, as will be better understood later.

At a point a short distance below the pivot a contact rod 28 extends across between the arms 20, being insulated therefrom by the blocks 29; and this rod carries a suitable 25 binding post or device 30 from which a conductor wire 31 preferably leads upwardly over the pivot and then down along the adjoining wall of the body and out through an opening 32. Thus the movement of the 30 pendulum is substantially uninfluenced by the conductor, and the latter is held out of the way.

The reflector 19 has a suitable metallic lamp socket 35 and a clip or bracket 38, welded or blazed thereto, these elements together forming a support for a fixture which, in this instance, includes the downwardly extending trough-like body 39 and the rearwardly extending arm 40 also of 35 dished cross-section. This fixture, which is preferably of sheet metal, is fastened to the downturned end 38' of the clip 38, as by means of the screw 41 and nut 42 which also serve both as a binding post for the positive 40 wire 43 and as securing means for the conductor 44, it being observed that the latter as well as the screw 41 and nut 42 are insulated from the bracket, and that the conductor 44 is insulated from the fixture 45 45 39-40, by the insulating block 45 and washer 46. At its extreme lower end 47 the element 39 assumes a tubular form and carries an insulator block 48 that in turn receives a metallic lamp socket 49 having an 50 arm 50 and binding screw 51 or other suitable means for attaching the negative conductor 52. When the corresponding or tail light bulb 53 is in place, its upper end bears 55 against the resilient loop 54 of the conductor 44.

In like manner, when the signal light bulb 56 is inserted in the socket 35, it is in resilient engagement with the upper end of the conductor 44, and the socket 35 and element 40 are charged (through the filament

of the lamp 56) whenever voltage is impressed on the wire 43. The part 40 forms a rigid support for a pair of thin contact strips 60-61 secured thereto as by the rivets 62 and having their upper ends spaced somewhat from the contact bar 28 when the pendulum is in neutral position so that a circuit may be completed through one or the other depending on the direction of swing. The wires 31-43 lead to a source of current such as the battery 65, the circuit being controlled by a switch 66 that may be mounted on the dash board; and the wire 52 may be directly attached to the wire 31 at the point 68 or in indirect connection 80 through the medium of a suitable switch and the conductor 52.

The particular switch shown, Figs. 1 and 6, which is inexpensive and well adapted to the purpose, includes the base 70 of insulating material riveted or otherwise fastened to the body concentrically to the opening 32 and having binding screws or posts 71-71' for the wires 52-52', the corresponding rounded contact pieces 72-72' being best 90 shown in Fig. 6. Alternating with the pieces 72-72' are a pair of diametrically arranged rounded lugs or projections 73-73' formed on the base 70. The movable element of the switch consists in the shaft 75 95 which is rotatable by the insulating handle 76 and which carries the oppositely disposed resilient arms 77-77' having backward extensions 78-78' forming depressions adapted to engage over the rounded contacts 100 72-72' or the lugs 73-73', as the case may be. Various other types of switches may, of course, be used.

Operation:—The device being mounted on the rear of the vehicle and both switches being closed, it is evident that a circuit is completed through the bulb 53 to give the usual tail light indication, and the rays may also pass down through an opening 80 formed in the lower side of the cylinder 5 110 and screened by a glass or other transparent sheet 81 held in place by lugs 82 struck from the body. Assuming that the vehicle is running at a constant speed the pendulum hangs in neutral position, but in the event 115 of the application of the brakes or of the starting of the car the inertia of the pendulum causes it to swing and alternately complete the signal circuit through the elements 60-61 so that a flickering or scintillating effect is then secured. In this action the circuit is broken while the pendulum swings between the two inner dashed line positions, Fig. 1, and is completed at all other times, but it is obvious that one of the 125 contact springs, say the element 60 might be omitted. The cushioning effect of these members is very gradually applied, and the length of the pendulum is such that a relatively rapid vibration is secured. If desired, that 130

portion of the lens which corresponds to the reflector 19 may be lettered as shown in Fig. 4; and it may differ in color from the part of the lens which corresponds to the 5 bulb 53, for example, the latter may be green and the former red.

By turning the switch 70—78 to break the conductor 52—52', the tail light bulb 53 may be shut off and the bulb 56 alone used, as 10 may be desirable when driving on dark days; and in any event the device utilizes the wiring of the ordinary tail light circuit.

The lamp fixtures and associated parts are 15 lifted out with the reflector 19 and may be readily replaced. If desired, the wire 52 may be passed through a hole in the base and looped at 52" outside the lamp, so that it may easily be drawn taut between the 20 pendulum arms.

We are aware that the details of the lamp, and the relative arrangement of parts are subject to considerable change. The particular construction shown has the decided 25 advantage, however, of utilizing the chamber 5 as a part of the pendulum space. We do not wish to be limited except as indicated by the subjoined claims.

We claim:—

- 30 1. A combined signal and tail lamp for vehicles, said lamp including a body, a tail light bulb in said body, a signal bulb also in said body and disposed at a higher level than the tail light bulb, a reflector for the 35 signal bulb and spaced considerably from the lower side of the body, and a pendulum for controlling the application of current to the signal bulb, said pendulum being swingable into the space below the reflector.
- 40 2. In a pendulum controlled signal lamp, a plurality of bulbs, a pendulum including a pair of spaced arms, means whereby the pendulum, on swinging, completes a circuit through one of the bulbs, one of the bulbs 45 being positioned between said arms and in the space described thereby in their swinging movement.
3. A combined signal and tail lamp including a body, a reflector detachably mounted therein, a bulb for the reflector, a second bulb carried by the reflector externally thereto, circuits for the bulbs, a divided pen-

dulum for controlling one of the circuits, the circuit for the second bulb including a conductor passing through between the 55 divisions of the pendulum.

4. A combined signal and tail lamp including a body, a reflector mounted in said body and having a substantially horizontal axis, a bulb socket for the reflector, a bracket 60 fixed to the reflector below said socket, a fixture carried on the bulb socket and said bracket, a second bulb supported on the lower end portion of the fixture, a threaded member for attaching the fixture to the 65 bracket, a circuit for one of the bulbs, said threaded member serving as a binding post for a part of said circuit.

5. A signal lamp for vehicles, said lamp comprising a body, a bulb, means for intermittently supplying current to the bulb as the speed of the vehicle changes, said means including a fixed resilient contact, a pendulum having two arms, and a second contact carried by the pendulum and insulated 70 therefrom, said second contact extending 75 across between the arms and being arranged to engage the first named contact.

6. A lamp comprising a body having a lens opening resembling the figure 8, a rib 80 along the bottom of the 8, a lens for said opening resting in the body behind the rib and along the haunches of the other lobe of the 8, and a latch for retaining the lens in the opening. 85

7. In a pendulum controlled signal lamp, a plurality of bulbs, one at a higher level than the other, a pendulum, means whereby the pendulum in swinging completes a circuit through one of the bulbs, the lower 90 bulb being positioned just above the space described by the bulb of the pendulum when swinging.

8. A signal lamp for vehicles including a body, a signal bulb in the upper portion of 95 said body, a reflector for said bulb and spaced considerably from the lower side of the body, and a pendulum for controlling the application of current to said bulb, said pendulum being swingable into the space 100 below the reflector.

GEORGE JACOBS.
FREDERICK C. RUPPEL.
